UNITED STATES PATENT OFFICE

GEORGE R. McALLASTER, OF ROCHESTER, NEW YORK

DESIGN FOR A COMBINED ASH TRAY AND INCENSE BURNER

Application filed January 6, 1932. Serial No. 42,389. Term of patent 14 years.

To all whom it may concern:

Be it known that I, GEORGE R. McALLASTER, a citizen of the United States, residing at Rochester, in the county of Monroe and State of New York, have invented a new, original, and ornamental Design for a Combined Ash Tray and Incense Burner, of which the following is a specification, reference being had to the accompanying drawings, forming part thereof.

The object of this invention is to provide a new and ornamental design for a combined ash tray and incense burner comprising a fireplace having an apron or tray in front thereof and a receptacle for matches on either side of the fireplace.

In the drawings:

Figure 1 is a front elevation of the ash

tray showing a fireplace with an apron, or tray, or platform extending out forwardly therefrom.

Figure 2 is a top plan view of the ash tray, showing a chimney central thereof with a flattened deck surrounding the top of the chimney and a receptacle for matches on each side of the chimney, together with an apron or platform extending out from the fireplace forming a tray.

Figure 3 is a side elevation of the design shown in Figures 1 and 2.

I claim:

The ornamental design for a combined ash tray and incense burner, as shown and described.

In testimony whereof I affix my signature.
GEORGE R. McALLASTER.
